[57] ABSTRACT

A compound of the formula

[in which R is H, halogen, alkyl having 1 to 4 carbon atoms or trifluoromethyl, and R₁ and R₂ each is H or dialkylaminoalkyl or together with N comprise methylpiperazino.] in which (I)

is —NH₂ and R is H, m-CH₃, o-CF₃, m-Cl, p-Cl, m-Br, m-F, p-F, o-F, p-CH₃, or m-CH₂, or

and R is H, m-CF₃ or m-F, or

and R is H, m-CF₃ or m-F.

The compound is prepared by treating the corresponding 5-hydroxymethyl compound with ammonia or an amine in the presence of phosgene.

The compounds possess anti-depressive, myorelaxing, tranquilizing, sedative, analgesic, anti-convulsive, anti-pyretic, anti-inflammatory and uricosuric activities.

**DERIVATIVES OF
5-CARBAMOYLOXYMETHYL-3-SUBSTITUTED-2-
OXAZOLIDINONES, PROCESS OF
PREPARATION THEREOF AND THERAPEUTIC
APPLICATION**

Matter enclosed in heavy brackets [ ] appears in the original patent but forms no part of this reissue specification; matter printed in italics indicates the additions made by reissue.

This application is related to our application Ser. No. 20,020, filed Mar. 16, 1970 *now abandoned*.

The present invention concerns novel derivatives of 5-carbamoyloxy-methyl-3-substituted-2-oxazolidinone, their process of preparation and their therapeutic application.

The compounds according to the present invention correspond to the general formula:

[in which:]

[R is a hydrogen atom, a halogen atom, an alkyl radical having 1 to 4 carbon atoms or a trifluoromethyl radical; and]

[R₁ and R₂ each represent a hydrogen atom or a dialkylaminoalkyl radical, or together with the nitrogen atom to which they are attached form a 40-methylpiperazino radical.]

in which (1)

is -NH₂ and R is H, m-CF₃, o-CF₃, m-Cl, p-Cl, m-Br, m-F, p-F, o-F, p-CH₃ or m-CH₃, or

and R is H, m-CF₃ or m-F, or

and R is H, m-CF₃ or m-F.

The process for the preparation of the compounds according to the present invention comprises treating an oxazolidinone of the general formula:

in which R has the same significance as in Formula I, with phosgene in the presence of ammonia or an amine of formula:

15

in which R₁ and R₂ have the same significance as in Formula I.

The oxazolidinone of Formula II is prepared by cyclising, by the action of ethyl carbonate, a 1-phenylamino-2,3-propanediol of the general formula:

in which R has the same significance as in Formula I.

The following preparation is given, by way of non-limitative example, to illustrate the present invention.

EXAMPLE

5-carbamoyloxymethyl-3-m-trifluoromethylphenyl-2-oxazolidinone (Code No. 68175).

(1) Preparation of 5-hydroxymethyl-3-(m-trifluoromethylphenyl)-2-oxazolidinone (Code No. 68121).

59 g. of 1-(m-trifluoromethylphenylamino)-2,3-propanediol and 118 g. of ethyl carbonate are introduced into a distillation apparatus. The mixture is progressively heated to about 110° C. when dissolution is obtained. Then, 12 ml. of 5% solution of sodium methylate in methanol is added thereto. The distillation of the ethanol formed in the course of the reaction is then observed. Upon completion thereof, any excess ethyl carbonate is removed under reduced pressure; the solid residue obtained is crystallised in isopropyl ether.

Melting point = 80° C.

Yield = 80%.

50 Empirical formula = C₁₁H₁₀F₃NO₃.

Elementary analysis.—Calculated (percent): C, 50.58; H, 3.86; N, 5.36. Found (percent): C, 50.74; H, 3.76; N, 5.56.

(2) Preparation of 5-carbamoyloxymethyl-3-m-trifluoromethyl phenyl-2-oxazolidinone.

300 ml. of a 20% solution of phosgene in toluene is rapidly added to a solution of 100 g. of 5-hydroxymethyl-3-(m-trifluoromethylphenyl)-2-oxazolidinone in 250 ml. of benzene. 63 g. of N,N-diethylaniline is then slowly added thereto with agitation. The hydrochloride which precipitates is dried and the clear organic solution also obtained is treated with a rapid current of gaseous ammonia. The solution is then treated with water, decanted and the organic phase is concentrated. 65 The solid residue obtained is crystallised in absolute ethanol.

Melting point = 123° C.

Yield = 50%.

Empirical formula = $C_{12}H_{11}F_3N_2O_4$.

Elementary analysis.—Calculated (percent): C, 47.37;

I prepared according to the second part of the above example.

H, 3.64; N, 9.21. Found (percent): C, 47.50; H, 3.86; N, 9.39.

The following Table I lists a certain number of intermediate compounds of Formula II prepared according to the first part of the above example, and Table II enumerates a certain number of compounds of Formula

The compounds of Formula I experimentally exert anti-depressive, myorelaxing, tranquillising, sedative, analgesic, anti-convulsive, anti-pyretic, anti-inflammatory and uricosuric activities. Moreover, their toxic effects on animals in the laboratory are little marked.

(I)—Anti-depressive properties

The compounds of Formula I are capable of opposing hypothermia and the ptosis provoked by reserpine in the rat and the mouse, as well as the ulcers provoked by reserpine in the rat. Moreover, they oppose the catalepsy provoked by prochlorperazine in the rat.

By way of example, several results obtained are listed in the following table:

TABLE III

Code Number	Ptosis							
	Hypothermia		Rat		Mouse		Ulcers	
Dose ¹	Effect, °C.	Dose ¹	Effect, percent	Dose ¹	Effect, percent	Dose ¹	Effect, percent	Dose ¹
6878	200	-3.4	200	53	200	55	200	60

69254	—	—	—	—	100	54	—	—
69263	—	—	—	—	100	50	—	—

¹Expressed in mg./kg./P.O.

(II)—Myorelaxing properties

The compounds of Formula I provoke in the mouse the loss of the righting reflex and inhibit the traction reflexes and the maintenance on a rotating rod.

By way of example, for the compound No. 68175, the ED_{50} in the traction test and also on the rotating rod is 130 mg./kg./P.O.

(III)—Tranquillising and sedative action

These effects are shown by a diminution of the exploration curiosity in the enclosure of an actimetric cage and of escape in an open field. The compounds of Formula I reduce the aggressiveness provoked by the passage of an electric current and lower the body temperature of animals. The narcotic effects of penthiobarbital are equally reinforced.

The results obtained with two compounds of Formula I are listed in the following table:

TABLE IV

Code Number	Actimetric			Evasion test			Potentialisation of penthiobarbital	
	Dose ¹	Effect, percent	Dose ¹	Effect, percent	Dose ¹	Effect, percent	Dose ¹	Effect, percent
6878	—	—	—	—	—	—	180	50

	Dose ¹	Effect, percent	Dose ¹	Effect, percent	Dose ¹	Effect, percent
68175	95	50	200	50	100	60

¹Expressed in mg./kg./P.O.

5

(IV)—Analgesic activity

This activity is particularly pronounced against the painful stretching provoked in the mouse by the intra-peritoneal administration of phenyl benzoquinone or acetic acid.

The results obtained with two compounds of Formula I are shown in the following table:

TABLE V

Code Number	Protection against phenyl benzoquinone	
	Dose in mg./kg./P.O.	Effect, percent
68175	62	60
6902	100	40

(V)—Anti-convulsive properties

The compounds of Formula I exert in the mouse an antagonism against the lethal effects of cardiazol, strychnine and nicotine. They equally show activity against the tonic hyperextension of an excessive electric shock.

By way of example, the results obtained with several compounds of Formula I are listed in the following table:

TABLE VI

Code Number	Antagonism against-					
	Cardiazol		Strychnine		Nicotine
